UNITED STATES PATENT OFFICE

CLAUD T. MILLER, OF HARVEY, ILLINOIS, ASSIGNOR TO THE BUDA COMPANY, OF HARVEY, ILLINOIS, A CORPORATION OF ILLINOIS

CARSTOP

Application filed May 2, 1931. Serial No. 534,565.

This invention pertains to railway car stops, its purpose being to provide a car stop that may be economically manufactured, readily installed by unskilled labor without the use of numerous or special tools, which occupies relatively small track space, which cushions the impact of the car, and which may be applied equally well to worn or new rails.

In accordance with this invention two stops are preferably employed, one being anchored to each rail. Each stop is also preferably constructed of a pair of shoes or plates adapted to engage the wheel of a car, the shoes being rigidly clamped to the bed or base of the rail, being free of the head thereof and being so shaped as to cushion the impact by raising the wheel engaged prior to finally stopping the wheel.

A better understanding of this invention will be obtained from the following description given in connection with the drawing which illustrates one embodiment of the invention and in which:

Fig. 1 is a perspective of a car stop applied to one rail and illustrating the cushioning action,

Fig. 2 is a front elevation of one of the stops,

Fig. 3 is a partial section taken on the line 3—3 of Fig. 2, and

Fig. 4 is a side elevation of a single stop illustrating the cushioning action by raising the wheel.

It is preferable to use a pair of stops, one for each rail, each stop being the same, however, only one is shown and only one will be described. Each stop comprises a pair of complementary shoes or plates 1 arranged to be rigidly clamped together upon opposite sides of a rail 2.

The shoes are preferably of cast malleable iron and are of the same configuration in reverse order, that is, they are complementary in order that they will fit upon opposite sides of the rail. The shoes are formed with an upper head or wheel engaging portion 3 having an inclined surface in the form of a curved forward edge 4 formed upon a radius equal to that of a standard car wheel when the stops

are to be used against such wheels. The curved edge 4 is formed upon a center at a distance above the rail slightly in excess of the distance of the car wheel center from the rail whereby when the car wheel strikes the curved edge 4 it will ride upwardly a short distance before engaging the entire surface and coming to a complete stop. This action will raise the wheel and car end and serve to cushion the impact of the wheel and more readily bring the car to a standstill without danger of damage to the running gear.

In order that the shoes may be securely fastened to the rails and to worn rails equally as well as to new rails, the shoes are clamped to the bed of the rail rather than to the head of the rail. For this purpose the bottom of the shoes are provided with outwardly opening tapered grooves 6 proportioned to receive the tapered bed flanges of the rail for which they are designed. The lower portion of the shoes are thickened and provided with aligned apertures to receive clamping bolts 7 which in cooperation with clamping bolts 8 draw the shoes together tightly against the bed of the rail. The shoes above the clamping groove 6 are cut away as at 9 to provide clearance so that the shoes will not contact the head of the rail when in position, but will be clamped to the base independently of the head. The upper ends of the shoes are also bored to receive a bolt 11 by means of which the upper ends of the shoes may be secured together. Suitable distance washers 12 may be inserted between the shoes to properly space the upper terminating ends of the two shoes. To add strength and greater rigidity to the stops, the shoes may be provided with vertical strengthening ribs 13 along the clamping portions and a marginal flange 14 along the rear edge of the shoe.

In order to transmit the force of the impact to a tie and thence to the ballast, the shoes are provided along the base thereof with a downwardly projecting abutment 16 which is arranged to engage the front vertical edge of a tie. This abutment also causes the stop to serve as an anti-creep device in one direction.

It will be apparent from the above that

when a pair of complementary shoes are rigidly secured in position and clamped to the base of a rail repeated impacts will not affect the vertical position of the stop, that is, the stop will always remain in perfect alignment with the wheel. Furthermore, the worn condition of the head of the rail will have no effect on the vertical position of the stop. It is apparent that no tools other than a wrench are necessary to apply the stop and that the stop may be applied by common rather than skilled labor, no drilling nor spacing of ties being required. It has been found that in actual installations the size of a stop may be such as to take up very little track space. In many installations for use in standard gauge rails the space occupied will be in the order of 16 inches.

It is obvious that many changes may be made in the details of construction from that embodiment illustrated without departing from the spirit and scope of this invention as defined in the claims appended hereto.

I claim:

1. A railway car stop comprising a shoe having a wheel engaging head portion and means for clamping said head portion to the base of a track rail whereby the head is supported from the base of the rail independently of the head of the rail.

2. A railway car stop comprising a pair of complementary shoes arranged to lie upon opposite sides of a rail and terminating at one end in wheel engaging portions and means for clamping said shoes to the base of a track rail independently of the head of the rail.

3. A railway car stop comprising a pair of complementary shoes adapted to lie upon opposite sides of a rail and terminating at one end in wheel engaging portions, said shoes being provided upon their other ends with grooves each adapted to receive opposite portions of the base of a track rail independently of the head of the rail, and means for drawing said shoes together to clamp opposite portions of the base of the rail rigidly therebetween.

4. A railway car stop comprising a pair of complementary shoes adapted to lie upon opposite sides of a rail and terminating at one end in wheel engaging portions, said shoes being provided upon their other ends with grooves each adapted to receive opposite flanges of the base of a track rail, and means for drawing said shoes together to clamp portions of the rail rigidly therebetween.

5. A railway car stop comprising a pair of complementary shoes adapted to lie upon opposite sides of a rail and terminating at one end in wheel engaging portions, said shoes being provided upon their other ends with grooves each adapted to receive opposite flanges of the base of a track rail, and means for drawing said shoes together to

clamp portions of the rail rigidly therebetween, said shoes being spaced from the head of the track rail when in position.

6. A railway car stop comprising a shoe having a wheel engaging head portion and means for clamping said head portion to the base of a track with the head portion above the track in position to receive the impact of a car wheel, said head portion being arranged to raise the wheel to cushion the impact.

7. A railway car stop comprising a shoe having a wheel engaging head portion and means for clamping said head portion to the base of a track with the head portion above the track in position to receive the impact of a car wheel, said head portion having an inclined surface arranged to raise the wheel to cushion the impact.

8. A railway car stop comprising a shoe having a wheel engaging head portion and means for clamping said head portion to the base of a track rail whereby the head is supported from the base of the rail independently of the head of the rail with the head portion above the track in position to receive the impact of a car wheel, said head portion being arranged to raise the wheel to cushion the impact.

9. A railway car stop comprising a shoe having a wheel engaging head portion and means for clamping said head portion to the base of a track, said wheel engaging portion being arcuate upon a radius substantially equal to the radius of the wheel to be engaged, the center of the arcuate wheel engaging portion being a greater distance from the track than the center of the wheel to be engaged.

10. A railway car stop comprising a shoe having a wheel engaging head portion and means for clamping said head portion to the base of a track rail whereby the head is supported from the base of the rail independently of the head of the rail, said wheel engaging portion being arcuate upon a radius substantially equal to the radius of the wheel to be engaged, the center of the arcuate wheel engaging portion being a greater distance from the track than the center of the wheel to be engaged.

11. A railway car stop comprising a pair of complementary shoes arranged to lie upon opposite sides of a rail and terminating at one end in wheel engaging portions and means for clamping said shoes to the base of a track rail independently of the head of the rail, said wheel engaging portions having inclined surfaces arranged to raise the wheel to cushion the impact.

12. A railway car stop comprising a pair of complementary shoes adapted to lie upon opposite sides of a rail and terminating at one end in wheel engaging portions, said shoes being provided upon their other ends

with grooves each adapted to receive opposite portions of a track rail, and means for drawing said shoes together to clamp opposite portions of the rail rigidly therebetween, 5 said wheel engaging portions having inclined surfaces arranged to raise the wheel to cushion the impact.

13. A railway car stop comprising a shoe having a wheel engaging head portion and 10 means for clamping said head portion to the base of a track rail whereby the head is supported from the base of the rail independently of the head of the rail, said shoe being provided with a downwardly projecting 15 abutment adapted to engage a tie.

14. A railway car stop comprising a pair of complementary shoes arranged to lie upon opposite sides of a rail and terminating at one end in wheel engaging portions and 20 means for clamping said shoes to the base of a track rail independently of the head of the rail, said shoes being provided with downwardly projecting abutments adapted to engage a tie.

25 15. A railway car stop comprising a pair of complementary shoes adapted to lie upon opposite sides of a rail and terminating at one end in wheel engaging portions, said shoes being provided upon their other ends 30 with grooves each adapted to receive opposite portions of a track rail, and means for drawing said shoes together to clamp opposite portions of the rail rigidly therebetween, said shoes being provided with downwardly 35 projecting abutments adapted to engage a tie.

In witness of the foregoing I affix my signature.
